[57] CLAIM

The ornamental design for a breakaway security cable tie, as shown and described.

DESCRIPTION

FIG. 1 is a front isometric view of the breakaway security cable tie;

FIG. 2 is an enlarged fragmentary perspective view of the front portion of the breakaway security cable tie;

FIG. 3 is a front isometric view of the breakaway security cable tie disposed in a locked position;

FIG. 4 is an enlarged, fragmentary front elevational view of the breakaway security cable tie in an unlocked position;

FIG. 5 is an enlarged, fragmentary right side elevational view of the breakaway security cable tie with the opposite side being a mirror image;

FIG. 6 is an enlarged, fragmentary rear elevational view of the breakaway security cable tie; and,

FIG. 7 is a fragmentary, sectional view taken along line 7—7 of FIG. 6.

The breakaway security cable tie is shown broken away in FIGS. 4-7 for ease of illustration.
